Primary Examiner — Paula Allen Greene*(74) Attorney, Agent, or Firm* — MARSHALL, GERSTEIN & BORUN LLP(57) **CLAIM**

The ornamental design for a crematory urn, as shown and described.

DESCRIPTION

FIG. 1 is a front, right and top perspective view of a crematory urn showing the new design;

FIG. 2 is a rear, left and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged detail view of the portion of FIG. 1 surrounded by the dot-dashed rectangle labeled as reference numeral 9.

The dot-dashed broken lines surrounding a portion of the crematory urn in FIG. 1 and included at the outer perimeter of the enlarged view of FIGS. 9 form no part of the claimed design.
